CLAIM

The ornamental design for a outdoor cabinet, as shown and described.

DESCRIPTION

FIG. 1 is a perspective view of a outdoor cabinet according to a first embodiment.

FIG. 2 is a front view of the outdoor cabinet of FIG. 1.

FIG. 3 is a back view of the outdoor cabinet of FIG. 1.

FIG. 4 is a left side view of the outdoor cabinet of FIG. 1.

FIG. 5 is a right side view of the outdoor cabinet of FIG. 1.

FIG. 6 is a top view of the outdoor cabinet of FIG. 1.

FIG. 7 is a bottom view of the outdoor cabinet of FIG. 1.

FIG. 8 is an illustration of the outdoor cabinet of FIG. 1 as part of a first exemplary outdoor kitchen; and,

FIG. 9 is an illustration of the outdoor cabinet of FIG. 1 as part of a second exemplary outdoor kitchen.

The broken lines depict environment and form no part of the claimed design. Shade lines are not an indication of surface texture or gloss.
